No. 36,979.

Patented June 14, 1904.

UNITED STATES PATENT OFFICE.

LEOPOLD HAUSER, OF NEW YORK, N. Y.

DESIGN FOR A WAIST-BELT.

SPECIFICATION forming part of Design No. 36,979, dated June 14, 1904.

Application filed March 11, 1904. Serial No. 197,718. Term of patent 7 years.

To all whom it may concern:

Be it known that I, LEOPOLD HAUSER, a citizen of the United States, residing in New York city, borough of Manhattan, New York, have
5 invented a new, original, and ornamental Design for Waist-Belts, of which the following is a specification, reference being had to the accompanying drawing, forming part thereof, which is a face view of a waist-belt, showing
10 my design.

What I claim, and desire to secure by Letters Patent, is—

The ornamental design for a waist-belt substantially as shown.

LEOPOLD HAUSER.
